TRAY FOR A FOOD PACKAGE

James T. Burns, Chicago, Ill., assignor to Wimpy Fresh Frozen Foods, Inc., Chicago, Ill., a corporation of Illinois

Application June 28, 1957, Serial No. 46,776

Term of patent 14 years

(Cl. D58—26)

Fig. 1

Fig. 2

Fig. 3

Fig. 4

Fig. 1 is a perspective view of a tray for a food package showing my new design;

Fig. 2 is a top plan view thereof;

Fig. 3 is a side elevational view thereof; and

Fig. 4 is a bottom plan view thereof.

I claim:

The ornamental design for a tray for a food package, as shown.
